By his Attorneys,

C. D. Howes & Co.

Inventor
D. C. Purvis

UNITED STATES PATENT OFFICE.

DAVID CULLEN PURVIS, OF PARAGOULD, ARKANSAS.

FIRE-PLACE.

SPECIFICATION forming part of Letters Patent No. 375,195, dated December 20, 1887.

Application filed April 15, 1887. Serial No. 234,940. (No model.).

To all whom it may concern:

Be it known that I, DAVID CULLEN PURVIS, a citizen of the United States, residing at Paragould, in the county of Greene and State of 5 Arkansas, have invented a new and useful Improvement in Fire-Places, of which the following is a specification.

My invention relates to an improved fire-place; and it consists in the construction, arrangement, and adaptation of the several parts 10 of the same, which will be more fully herein-after described, and pointed out in the claims.

One object of my invention is to provide an improved fire-place and grate, the parts of 15 which are constructed separately and adapted to be bolted together and mounted as a whole, or to be interchanged by new parts when the old parts shall have become worn or broken.

A further object of my invention is to provide 20 a fire-place and grate which is simple and effective in its construction and operation, strong and durable, easily handled and readily understood, convertible for the use of either wood or coal, quickly set up in operative 25 position, and comparatively inexpensive in manufacture.

I attain these objects by the construction illustrated in the accompanying drawings, wherein like letters of reference indicate similar parts in the several views, and in which— 30

Figure 1 is a perspective view of my improved fire-place and grate before being set up in position in the wall. Fig. 2 is a front elevation of my fire-place and grate in position 35 in the wall with the deflector-plate removed. Fig. 3 is a transverse vertical section on the line $x-x$ of Fig. 2.

A indicates the hearth, which may be constructed of a single piece of metal or in 40 visional strips, and may be either square, rectangular, or oval in form, as the taste and construction may require. Secured to each side of the hearth A are two metallic jambs, B B, which are of suitable configuration at their 45 front, rear, and top portions as to adapt them to receive the several parts to be connected thereto, and also to present a pleasing design and appearance, which may be varied as is desired. The top portions of these jambs B 50 are circular in form for the reception of the arched plate F, upon which the brick-work

rests when the furnace is set up in the wall. To the forward portion of the said jamb B a deflector-plate, E, is connected, and formed with a hinged joint, so that it can be lowered 55 to deflect the heat toward the flue or raised to allow the heat to enter the room or apartment. To the rear lower portion of the jamb B a shield or back plate, C, is secured, to which is hinged a perforated damper-plate, D, which 60 projects to the forward part of the fire-place or grate, and is connected to the transverse damper-rod D', passing through the furnace and secured in the jamb-plate B. This damper-plate D is constructed and adapted to regulate 65 the draft of the fire-place, and also to control the exit of the smoke therefrom. A further object of this damper-plate, by means of its extended construction, is to act as a deflector for throwing the heat into the deflector-plate 70 E. Just in front of the plate C two removable shield or guard plates, J J, are mounted in the fire-place, which are formed with ribs to strengthen the same, and which are adapted to shield the rear portion of the fire-place in 75 the wall in the rear thereof, and are constructed removable for the purpose of being replaced by other plates of similar construction whenever such plates will have become worn or burned through by the action of the fire. On 80 the inner lower side of the jambs B removable shield-plates I I are secured by being slipped or slid in under grooved strips H H, secured to the sides of said jamb-plates. The inner sides of these plates I I are provided 85 with ribs to strengthen the same, which rest against the said jamb-plates, and on their opposite sides said plates I I are provided with projecting lugs i i, on which the grate G is adapted to be slid and rests.

In the bottom or ash-pit portion of said furnace or fire-place a removable plate, G', is placed for the purpose of further protection of the hearth-plate A against the fire in the grate, and to readily remove the ashes, as will 95 be readily understood. On each outer edge of the shield-plates I I suitable metallic eye-loops, i' i', are formed and secured thereto, which are adapted to receive the supporting-arms of swinging cranes J' J'. These swinging 100 cranes are adapted to receive cooking utensils and to be swung in over the fire, thereby

providing means for hurriedly providing food for the table. These cranes J J' are removable from the said loops, with which they engage, and when they are removed, a fender or 5 shield, d, may be placed in engagement with said loops for any purpose which may be desired.

It will be understood that the grate G may be removed from the fire-place and wood placed 10 upon the hearth or upon the shield-plate G' in a manner similar to the ordinary open wood fire.

The parts of my improved fire-place and 15 grate are constructed separately and afterward bolted together and adjusted, as herein-before set forth, and then set in connection with the wall, when it is ready for use.

It is obvious that many minor changes in 20 the construction and arrangement of parts may be made and substituted for those shown and described, without in the least departing from the nature and principle of my invention.

Having thus described my invention, I claim—

25 1. The combination of the jambs B B, the arch-plate F, at the upper ends of the same, the plate J, below the arch-plate F, and the perforated damper-plate D, between the arch-plate F and the plate J, substantially as set 30 forth.

2. The combination of the jamb-plates B B, the arch-plate F, the pivotally-mounted cylindrically-shaped deflector E, the rear plate, C, the plate J, having the curved extension, the extended perforate damper-plate D, adapted to be raised and lowered, and the damper-rod D', substantially as described. 35

3. The combination, with the jamb-plates B B, of the removable plates I I, having the sockets i secured thereto, said sockets being 40 adapted to receive swinging cranes or a shield-plate which may be interchangeably mounted, substantially as described.

4. The combination, with the jamb-plates B B, having the flanges H integrally formed therewith, of the removable plates I I, having the ribs formed therewith on one side adapted to rest against the jamb-plates, and flanges i, with the lower portions of the opposite sides to receive and form a rest for a removable grate, G, substantially as described. 45 50

In testimony that I claim the foregoing as my own I have hereto affixed my signature in presence of two witnesses.

DAVID CULLEN PURVIS.
